UNITED STATES PATENT OFFICE.

MAX HERSKOVITZ, DECEASED, LATE OF CHICAGO, ILLINOIS; BY WILLIAM HERSKOVITZ, EXECUTOR, OF CHICAGO, ILLINOIS.

ELECTRIC SOCKET STRUCTURE.

Application filed November 22, 1924. Serial No. 751,697.

To all whom it may concern:

Be it known that MAX HERSKOVITZ, deceased, formerly a citizen of the United States, lately residing at Chicago, Illinois (William Herskovitz, executor), has invented new and useful Improvements in Electric Socket Structures, of which the following is a specification.

This invention relates to electrical devices comprising a body, or housing, member for receiving, and housing, an electrical contact-equipped socket for an electric lamp. The primary objects of the invention are to provide a novel, simple and inexpensive construction of body member, the parts of which may be readily assembled and disassembled, as desired; to provide such a body member as a part of a lamp structure and serving as means for supporting a shade support; to provide such a body member as a part of a reflector-equipped structure, the reflector of which is carried by the body member; and to provide a structure whereby the electric light socket may be introduced into and removed from, its housing structure, at will, without disturbing the connection of the housing member with the part on which it is supported and without disturbing the shade support, or reflector, as the case may be.

Referring to the accompanying drawings:

Figure 1 is a view in elevation of a table lamp embodying the invention, the lower part thereof being broken away and the shade, together with a member from which it is directly supported, being shown in section. Figure 2 is a view in elevation of one of the sections of the body member and shade support of the structure. Figure 2a is a face view of the other section of the body member, this view showing the inner surface of the latter. Figure 3 is a section taken at the line 3 on Fig. 2, showing the body member only. Figure 4 is a section taken at the line 4 on Fig. 2 and viewed in the direction of the arrow. Figure 5 is a face view of a reflector-equipped socket structure embodying the invention. Figure 6 is a similar view viewing the structure of Fig. 5 from a point normal to that from which the structure of Fig. 5 is viewed; and Figure 7, a section taken at the line 7 on Fig. 5 and viewed in the direction of the arrows, the reflector portion being shown partly broken away.

Referring to the structure shown in Figs. 55 1 to 4, inclusive, wherein the invention is illustrated as embodied in a table lamp, the standard portion of the lamp is represented at 8 and as is usual in constructions of this character, contains an upright tube 9 through 60 which the electric-current-conducting wires for the lamp socket of the device and represented at 100, extend. The tube is surrounded by an electric socket structure embodying the invention and which forms a 65 housing for the socket 100, and comprising, in the particular embodiment illustrated, a socket-forming body, or housing, member formed of sections 10 and 11 which may be, and preferably are, of cast metal. The 70 sections 10 and 11 are each, of substantially semi-circular shape in cross section as shown, the joint at which these sections fit together throughout the greater portion of their length, extending lengthwise of the body 75 member, and the section 10 having its lengthwise-extending edges provided with outwardly offset flanges 12 for partially embracing the adjacent edges of the section 11, as shown in Fig. 4, when the sections are 80 assembled to the position therein shown.

The lower end of the body member is closed by a plate portion 13 formed integrally with the section 10 and containing a centrally disposed boss 14 containing a 85 screw threaded aperture 15 for receiving the upper threaded end of the tube 9, which latter screws into it. The plate 14 is of such dimensions that a portion of its marginal edge overlaps the lower end portion of the 90 section 11, as shown, and forms a joint.

The socketed body thus provided is adapted to receive the lamp socket 100, which upon assembly, is positioned in the socket body as shown in Fig. 2, with its external 95 portion surrounded by a sheathing of current insulating material as is common practice. The socket shown is of the common pull-chain type, the guide tube 16 of which, and in which the pull-chain represented at 100 17 operates, extending through registering recesses 18 in opposing edges of the sections 10 and 11. Upon assembling the sections 10 and 11 about the lamp socket 100, these sections are clamped together, as for example, 105 and preferably, by a screw 19 which extends cross-wise of the body member below the lamp socket 100 and screws into an aper-

tured boss 20 formed on the inner surface of the section 10.

The body member carries a shade-supporting member 21 which is shown as carried by, 5 and is preferably formed integrally with, one of the sections 10 or 11, but preferably section 10, as shown, the member 21 being shown of general loop form presenting upwardly extending spaced, diametrically opposed, arms 22 joined together at their upper ends by a shade-seating disk-like portion 23. In the particular construction illustrated the member 10 with its end plate 13 and the supporting member 21, are 10 formed integrally, and preferably by casting these parts as a unitary structure.

When the shade, represented at 24, is of the type shown, namely, with a comparatively large central opening 25, a shade-clamping member 26 is provided which rests at 20 its central portion upon the top surface of the member 23 and is secured thereto as by a screw 27, extending through the member 26 and screwed into the member 23, the member 26 being provided with shade engaging and supporting set screws 28, as is usual in structures of this general type.

Referring to the structure shown in Figs. 5, 6 and 7, wherein the invention is illustrated in a structure adapted for support in a variety of ways, as for example, as in the case of the usual adjustable lamp bracket fixture, or adjustable desk lamp, the structure shown comprises a socket forming body, 30 or housing, member 29 of the same construction as in the case of the body member of the preceding figures of the drawings, except that this body member is shown of greater length to adapt it to house at its lower end portion, "a plug-in" switch (not shown) of any desirable construction, and instead of being provided with a lamp supporting member, as for example the member 22 of the preceding figures of the drawings, is provided with a reflector portion 30 which extends outwardly from the body member to one side of its longitudinal axis, and is so positioned as to partially surround the electric lamp illustrated at 31 and 35 screwed into the lamp socket of the structure, the reflector member 30 being preferably carried by the one of the sections which carries the end-wall-forming plate of the body member, whereby the plate portion referred to and the reflector portion 30 are formed integrally with one of the sections comprising the body member.

It will be understood from the foregoing that a socket device constructed in accordance with the invention is not only of simple and economical construction, but is adapted for the disassembly of the sections forming the body member, for access to the interior thereof, as for example to remove, 60 or replace, the lamp socket therein, with-

out requiring disconnection of the body member from the part at which it is supported, it being necessary only that the section 11 be removed, to permit of the desired access to the interior of the housing. 70

While I have illustrated and described certain particular constructions embodying the invention, I do not wish to be understood as intending to limit the invention thereto, as the same may be variously modified and altered without departing from the spirit thereof. 75

What I claim as new, and desire to secure by Letters Patent, is:

1. An electric socket structure comprising 80 a hollow lamp-socket-housing member formed of separable sections with the joint therebetween extending lengthwise of said member, one of said sections having a portion extending crosswise of said housing member and forming the end wall of said member, and means for releasably securing said sections together. 85

2. An electric socket structure comprising 90 a lamp-socket-housing member formed of separable sections with the joint therebetween extending lengthwise of the member, one of said sections having formed integrally therewith a portion extending crosswise of 95 said housing member and forming the end wall of said member, and means for releasably securing said sections together.

3. An electric socket lamp structure comprising 100 a lamp-socket-housing and supporting member formed of separable sections with the joint therebetween extending lengthwise of said member, one of said sections having a portion extending crosswise of said housing member and by which said member is adapted wholly to be supported, 105 means releasably securing said sections together, and a shade-supporting member carried by one of said sections. 110

4. An electric socket lamp structure comprising 115 a lamp-socket-housing and supporting member formed of separable sections with the joint therebetween extending lengthwise of said member, one of said sections having a portion extending crosswise of 120 said housing member and by which said member is adapted wholly to be supported, means releasably securing said sections together, and a shade-supporting member carried by the one of said sections provided with said portion. 125

5. An electric socket lamp structure comprising 130 a lamp-socket-housing-and-supporting member formed of separable sections with the joint therebetween extending lengthwise of said member, one of said sections having an end-forming portion extending crosswise of said housing member and by which said member is adapted wholly to be supported, means releasably securing said sections together, and a fixture element car-

ried by one of said sections and extending lengthwise thereof and outwardly beyond said housing member.

6. An electric socket lamp structure comprising a lamp-socket-housing-and-supporting member formed of separable sections with the joint therebetween extending lengthwise of said member, one of said sections having an end-forming portion extending crosswise of said housing member and by which said member is adapted wholly to be supported, means releasably securing said sections together, and a fixture element carried by the one of said sections provided with said portion and extending lengthwise thereof and outwardly beyond said housing member.

7. An electric socket lamp structure comprising an upright, a lamp-socket-housing and supporting member formed of separable sections with the joint therebetween extending lengthwise of said member, one of said

sections having a portion extending crosswise of said member and by which said member is supported on said upright, means releasably securing said sections together, and an upwardly extending shade-supporting member carried by one of said sections.

8. An electric socket lamp structure comprising an upright, a lamp-socket-housing and supporting member formed of separable sections with the joint therebetween extending lengthwise of said member, one of said sections having a portion extending crosswise of said member and by which said member is supported on said upright, means releasably securing said sections together, and an upwardly extending shade-supporting member carried by the one of said sections which is provided with said portion.

WILLIAM HERSKOVITZ,
*Executor of the Estate of Max Herskovitz,
Deceased.*
